(21) Appl. No.: **29/160,607**

The ornamental design for a key chain clip, as shown.

(22) Filed: **May 15, 2002**

DESCRIPTION

(51) LOC (7) Cl. **03-01**

FIG. 1 is a top view of a key chain clip, comprising a clip bearing member, a movable key chain component linked to the clip and a third member, showing my new design;

(52) U.S. Cl. **D3/207**

FIG. 2 is a bottom view of FIG. 1;

(58) Field of Search D11/78.1, 215;
D3/207-212; 70/458, 456 R, 456 B; 24/488,
501, 563; 453/50; 206/27.1, 38.1; 150/147

FIG. 3 is a side view of FIG. 1;

(56) **References Cited**

FIG. 4 is an isometric view of FIG. 1;

U.S. PATENT DOCUMENTS

FIG. 5 is a side view of the key chain clip, wherein the movable key chain component is linked to the third member showing my new design; and,

D349,398 S * 8/1994 Ezzo D3/208
D362,959 S * 10/1995 Tran D3/208
D366,229 S * 1/1996 Barnett D3/208
D368,868 S * 4/1996 Velleco D11/78.1
D384,591 S * 10/1997 Richards D11/78.1
D428,823 S * 8/2000 Davi D11/78.1

FIG. 6 is an isometric view of FIG. 5.

The key ring shown in broken lines in FIGS. 1, 2, 3 and 4

is unclaimed portion in my new design.
